FLUORESCENT LIGHTING FIXTURE

Carl J. H. Nitardy, Ipswich, Mass., assignor to
Sylvania Electric Products Inc., Salem, Mass.,
a corporation of Massachusetts

Application February 28, 1950, Serial No. 8,189

Term of patent 14 years

(Cl. D48—23)

To all whom it may concern:

Be it known that I, Carl J. H. Nitardy, citizen of the United States, residing at Ipswich, in the county of Essex and State of Massachusetts, have invented a new, original, and ornamental Design for a Fluorescent Lighting Fixture, of which the following is a specification, reference being had to the accompanying drawing, forming part thereof.

Figure 1 is a bottom perspective view of a fluorescent lighting fixture showing my new design.

Figure 2 is a top plan view thereof.

Figure 3 is a side elevational view thereof.

Figure 4 is an end view thereof.

Figure 5 is a sectional view taken on the line 5—5 of Figure 3.

I claim:
The ornamental design for a fluorescent lighting fixture, as shown.

CARL J. H. NITARDY.
